ATTORNEY

UNITED STATES PATENT OFFICE

VICTOR GEORGE WILLIAM GILBERT, OF LONDON, ENGLAND, ASSIGNOR, BY MESNE ASSIGNMENTS, TO AMERICAN LA FRANCE AND FOAMITE CORPORATION, A CORPORATION OF NEW YORK

FIRE EXTINGUISHER

Application filed September 21, 1925, Serial No. 57,537, and in Great Britain December 10, 1924.

The object of this invention is to improve the action of extinguishers of the kind in which two solutions are separately contained and brought into mixing contact on inversion 5 for producing a fire-extinguishing medium particularly foam-type extinguishers in which such medium is foam. The object is to avoid the initial discharge, immediately on inversion of one of the solutions unmixed 10 with the other, by means of a simple and inexpensive construction.

In the accompanying drawing, Figure 1 represents an axial section of a standard form of extinguisher to which the invention has 15 been applied and Figure 2 a larger scale section thereof.

The extinguisher comprises a main or outer container 1 provided with a ring-form neck member or casting 2 threaded to receive the 20 usual screw cover 3 and also an inner container 4 which is seated at its lower end on the bottom of the outer container and provided at its upper end with a cage structure 25 which normally occupies, and is supported by, the opening in the neck casting, through which opening the inner container is intended to be removable as will be understood. The inner container is normally closed by a stopple 6 which may be gravity operated or 30 exteriorly operated, as desired. It will be understood that an acid solution is usually contained in the inner container and a basic solution in the outer container.

The discharge outlet from the extinguisher 35 is constituted by an elbow 7 and hose connection 8 of usual type, and the elbow is threaded into an opening 9 formed in the ring casting 2. This opening or passage 9 constitutes the entrance to the discharge outlet 40 and is extended inwardly so that its orifice is close to the point where the two solutions first come into contact when the extinguisher is inverted. Preferably such orifice is in line with the inner surface of the neck casting, 45 and it is faced either directly toward the cage of the inner container or upwardly, i. e., toward the screw cover, but not downwardly, so that it will be shielded from the first rush of basic solution on inversion. Preferably 50 also, the entrance is cone-shaped, or tapered,

as shown, which has the advantage, first, that it facilitates casting the ring member and second, that it provides a wide mouth entrance to the narrower elbow passage, thus making certain that both acid and basic solutions will initially pass into the hose. 55

On the inversion of this extinguisher, the initial contact of the two solutions occurs at about the location of the orifice and in consequence thereof, the initial delivery through such orifice consists of a mixture of the two solutions, resulting in the delivery of foam from the start, instead of an initial slug of liquid or watery foam as commonly the case in extinguishers of this class. The duration 60 of the foam stream is also increased. By locating the entrance section of the delivery passage in the neck casting, the correct position of the entrance orifice is easily and simply obtained without special manufacturing 65 operations and thereby an improved extinguisher is produced at extremely low cost. 70

Claim:

In an invertible foam extinguisher, an outer container adapted to hold one of the 75 foam forming solutions and having a cast metal neck-member provided with a cover, an inner solution container insertable through the neck opening and confined therein by said cover, said cast-metal neck-member being formed with a seat for said cover and with a lateral projection below said seat, said projection being hollow from a point substantially in line with the side of said neck opening at the level of the outlet from said 80 inner container, to a point outside of said outer container, and having a foam-delivery member secured to its outer end. 85

In testimony whereof I have hereunto affixed my signature. 90

VICTOR GEORGE WILLIAM GILBERT.
